COAXIAL LINE SECTION BASE

Philip F. Puljer, Parma, Ohio, assignor to Bird Electronic Corporation, Solon, Ohio, a corporation of Ohio

Filed Nov. 18, 1966, Ser. No. 4,734

Term of patent 14 years

(Cl. D26—5)

FIGURE 1 is a side elevational view of a coaxial line section base illustrating my new design;

FIGURE 2 is a front elevational view of the coaxial line section base;

FIGURE 3 is a bottom view of the coaxial line section base;

FIGURE 4 is a rear elevational view of the coaxial line section base; and

FIGURE 5 is a plan view of the coaxial line section base.

The undisclosed top of the coaxial line section base is substantially flat and plain.

The portions shown in dotted-lines in FIGURES 1, 2, 4 and 5 are for illustrative purposes only.

I claim:

The ornamental design for a coaxial line section base, substantially as shown and described
